[57] **CLAIM**

The ornamental design for an original feeder for electronic copying machine, substantially as shown.

DESCRIPTION

FIG. 1 is a front, top and left side perspective view of an original feeder for electronic copying machine showing our new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof;

FIG. 7 is a bottom plan view thereof; and

FIG. 8 is a perspective view of FIG. 1, the broken-line showing of a copying machine is environmental only and forms no part of the claimed design.

FIG. 1

FIG. 2

FIG. 3

FIG. 4

FIG. 7

FIG. 8
